UNITED STATES PATENT OFFICE.

EDWARD T. CURRAN, OF DETROIT, MICHIGAN.

DESIGN FOR AN AUTO THERMOMETER.

60,780.

Specification for Design. Patented Apr. 11, 1922.

Application filed March 9, 1921. Serial No. 450,971. Term of patent 3½ years.

To all whom it may concern:

Be it known that I, EDWARD T. CURRAN, a citizen of the United States, residing at Detroit, in the county of Wayne and State of Michigan, have invented a new, original, and ornamental Design for an Auto Thermometer, of which the following is a specification, reference being had to the accompanying drawing, forming part thereof.

The figure is a face view of auto thermometer, showing my new design.

I claim:

The ornamental design for an auto thermometer, as shown.

EDWARD T. CURRAN.
